UNITED STATES PATENT OFFICE.

ARTHUR BURTON, OF WINSLOW, ARIZONA.

HEADLIGHT-BULB SHADE.

Application filed January 8, 1926. Serial No. 80,058.

This invention relates to a shade for a headlight bulb for covering the top side of the same resulting in the dimming of the light above the horizontal plane of the light and thus preventing the blinding of the drivers of oncoming machines which is the cause of a great number of automobile accidents experienced today.

The primary object of my invention is to substantially improve and simplify shades of this general character heretofore used and patented.

In the attainment of this end I provide a shade that consists of a single piece of sheet metal so formed as to cover the upper half of the headlight bulb and also so formed as to permit of the ready attachment of the same to the bulb.

In the drawing wherein like reference characters indicate corresponding parts throughout both the views:

Figure 1 is an elevation of a conventional form of headlight bulb associated with the corresponding socket, on a part of which is disposed a shade constructed in accordance with the present invention the same being shown in full applied position and in partially applied dotted line position.

Figure 2 is an elevation similar to Figure 1, but taken at direct right angles thereto, and

Figure 3 is a detail transverse section taken substantially on the line 3-3 of Figure 1.

Now having particular reference to the drawing, my novel shade constitutes the provision of a single piece of sheet metal that is formed into a semi-bulbous shaped member 5 adapted for disposition over the usual headlight bulb A that is removably disposed within the usual socket B.

At one end of the semi-bulbous shaped head member is a reduced semi-circular neck 6 adapted for engagement around the plug portion a between the bulb A and the socket B. Formed upon the forward ends of said neck are inwardly and then outwardly turned spring ears 7-7 that will frictionally engage the plug portion a of said bulb A for maintaining the shade upon the bulb, as clearly shown in Figures 1 and 2.

In order that the shade will be prevented from turning upon the bulb, the neck por-

tion 6 of the shade is formed at one point and at its edge with a laterally extending tongue 8 that is adapted to engage within the forward end of one of the usual bayonet slots 9 of the lamp socket B, in a manner as clearly shown in Figure 1.

It will thus be seen that I have provided a highly novel, simple, and relatively inexpensive form of headlight bulb shade that will prevent the light rays from the bulb passing in an upward direction resulting in the blinding of the drivers of oncoming machines, the light rays from the bulb provided with a shade of the present character being prevented from passing above the horizontal axis of the bulb as clearly illustrated in the drawing.

Having thus described the invention, what I claim as new and desire to secure by Letters Patent is:—

1. In combination with a headlight bulb and its receiving socket that is provided at opposite sides with bayonet slots for receiving the usual pins of the bulb plug, a metallic semi-bulbous shaped member adapted for engagement over the top side of the headlight bulb, means at the inner end of said bulbous shaped member for engaging the exposed portion of the bulb plug for securing the shade upon the bulb and means at one point of the inner end of the semi-bulbous shaped member for engaging with in one of the lamp socket slots for preventing the turning of the shade upon the lamp bulb.

2. In combination with a headlight bulb and its receiving socket a semi-bulbous shaped member adapted for engagement over the top side of the bulb, means at the inner end of said semi-bulbous shaped member for engagement partially around the exposed portion of the bulb plug for retaining the shade upon the bulb, and a tongue upon the inner end of the semi-bulbous shaped member at one point thereon for engagement within one of the usual bulb plug pin receiving slots of said socket member for preventing the turning of the shade upon the bulb.

In testimony whereof I affix my signature.

ARTHUR BURTON.
